UNITED STATES PATENT OFFICE

133,259

DESIGN FOR A TABLE SCARF OR SIMILAR ARTICLE

Jack Schwab, Lawrence, N. Y.

Application July 3, 1942, Serial No. 107,405

Term of patent 3½ years

To all whom it may concern:

Be it known that I, Jack Schwab, a citizen of the United States, residing at Lawrence, Long Island, county of Nassau, and State of New York, have invented a new, original, and ornamental Design for a Table Scarf or Similar Article, of which the following is a specification, reference being had to the accompanying drawing, forming part thereof, wherein the figure is a plan view of a table scarf or similar article showing my new design.

I claim:

The ornamental design for a table scarf or similar article, substantially as shown.

JACK SCHWAB.
